United States Patent Office

Des. 184,244
Patented Jan. 6, 1959

184,244

PLATE OR SIMILAR ARTICLE

Shuzo Terano, Mizuho-ku, Nagoya, Japan
Application May 23, 1957, Serial No. 46,317

Term of patent 3½ years

(Cl. D44—15)

On the drawing the figure is a plan view of a plate or similar article, showing my new design.

The plate is of a conventional configuration when viewed from the side and bottom thereof.

I claim:

The ornamental design for a plate or similar article, substantially as shown and described.
